UNITED STATES PATENT OFFICE

2,535,166

BURNER NOZZLE WITH FLAME CONTROL
MEANS

Cecil W. Smith, Waterman, Ill.

Application September 29, 1947, Serial No. 776,662

3 Claims. (Cl. 299—120)

1

An object of this invention is to provide an improved nozzle for an oil burner.

Another object of this invention is to provide a nozzle for a burner capable of producing a spray or jet of uniform mixture characteristics, and of discharging such spray at a substantially uniform volume rate of flow so as to eliminate any uneven burning of the spray.

Yet another object of this invention is to provide a nozzle for an oil burner of a construction such that an efficient burning takes place of both the light and heavy ends of substantially all types of commercially available burner fuels.

A still further object of this invention is to provide a nozzle for an oil burner which is adapted to highly atomize an air and fuel mixture supplied thereto under pressures in the neighborhood of from three to four pounds per square inch.

Another object of this invention is to provide an oil burner nozzle adapted to eliminate any stratification of the air and fuel, in an air and fuel mixture flowing therethrough, and to maintain the fuel uniformly dispersed in the air to the zone of burning.

Still a further object of this invention is to provide an oil burner nozzle so constructed that burning of the air and fuel spray discharged therefrom takes place with substantially no noise and without any appreciable heating of the nozzle.

A feature of this invention is found in the provision of a nozzle for an oil burner which is formed with a system of inter-connected passages successively arranged in planes normal to each other. At least one junction of a pair of adjacent inter-connected passages has an expansion chamber or mixture-receiving pocket so arranged that the mixture admitted into the chamber from one of such passages is reversed in flow so as to travel against the incoming mixture prior to the continued flow of the mixture into the other passage.

Another feature of this invention is found in the provision of a nozzle for an oil burner having a passage system for an air and fuel mixture of a construction to provide for an increased velocity flow of the mixture prior to the flow of the mixture into an open chamber having a single opening, so that the mixture is thoroughly mixed and agitated by its expansion and reversed flow in such chamber whereby to eliminate any stratification of the air and fuel in the mixture.

Yet another feature of this invention is found in the provision of a nozzle for an oil burner in

2

which a passage system for an air and fuel mixture supplied to the nozzle is comprised of a plurality of interconnected longitudinal and transverse passages in which all of the longitudinal passages are in horizontal planes. At the junction of certain of the longitudinal and transverse passages, the system is formed with open mixture-receiving chambers having single openings in fluid registration with such junction, arranged to provide for a counter flow of the mixture into and out of the chambers whereby to eliminate any stratification of the air and fuel in the mixture. A swirling motion is imparted to the mixture spray discharged from the nozzle by means located adjacent to the outlet of the passage system. By virtue of the horizontal disposition of the longitudinal passages any uneven burning of the spray is overcome by merely rotating the nozzle about its longitudinal axis to an adjusted position in the direction of the lean burning portions of the spray.

Further objects, features and advantages of this invention will become apparent from the following description when taken in connection with the accompanying drawings, in which:

Fig. 1 is a top plan view of the oil burner nozzle of this invention;

Fig. 2 is a longitudinal sectional view of the nozzle taken along the lines 2—2 in Figs. 1 and 3.

Figs. 3, 4 and 5 are transverse sectional views as seen on the lines 3—3, 4—4 and 5—5, respectively, in Fig. 2;

Fig. 6 is a developed view of the nozzle body member;

Fig. 7 is a top plan view of the body member illustrated on a reduced scale relative to its showing in Fig. 2;

Fig. 8 is a diagrammatic showing of the passage system in the nozzle for the air and fuel mixture;

Fig. 9 is an enlarged fragmentary side elevational view of the front portion of the nozzle, with parts broken away;

Fig. 10 is a top plan view of a modified form of the invention having certain parts broken away to more clearly show its construction;

Fig. 11 is a transverse sectional view as seen along the line 11—11 in Fig. 10.

Fig. 12 is a longitudinal sectional view taken along the line 12—12 in Fig. 11.

With reference to the drawings, the nozzle of this invention is illustrated in Figs. 1 and 2 as including a body member 15, a plug or insert member 16 and a cap or casing member 17. The plug member 15 is of a generally cylindrical

shape provided with an axial bore 18 having a plurality of adjacent sections of varying diameters and shapes. Thus, as best appears in Fig. 2, the bore 18, from the rear end 19 of the plug member 15, is formed in succession with a forwardly and inwardly tapered internally threaded section 21 which terminates in a straight section 22; a forwardly and inwardly tapered section 23 terminating in a straight section 24; a straight section 26 of a greater diameter than the section 24; and a straight section 27 of a greater diameter than the section 26. The bore section 21 is adapted for connection with the threaded tapered end 28 of an air and fuel supply tube 30.

Extended transversely through the body member 15 and through the bore 18 at a position adjacent to the rear end of the bore section 26, is a fluid passage 29 (Figs. 2 and 3). The opposite ends of the transverse passage 29 are in fluid registration with circumferential grooves 31 (Figs. 3 and 7) formed in the peripheral surface of the body member 15 and extended in the same direction from the ends of the transverse passage 29 such that the ends 32 of the circumferential grooves 31 are arranged opposite each other at the top and bottom sides of the body member 15.

The ends 32 of the circumferential grooves 31 (Figs. 5, 6 and 7) are open to the rear ends of a pair of longitudinally extended grooves 33, the forward ends 36 of which are in fluid registration with circumferential grooves 34 at positions substantially intermediate the ends of the grooves 34. In turn the opposite ends 37 of the circumferential grooves 34 are fluid connected with the rear ends of longitudinal grooves 38, the front ends 39 of which are connected with openings 41 arranged in a spaced relation about the body member 15 and tangential to the section 27 of the bore 18.

From a consideration of Figs. 2 and 6, it is seen that the longitudinal grooves 33 are of a greater length than the longitudinal grooves 38, and that the combined length of these grooves is such that the inner ends 42 of the tangential openings 41 are open to the bore 18 at positions adjacent to the front end of the bore section 27. It will be further noted that all of the longitudinal grooves 33 and 38 are arranged in a parallel relation with the longitudinal axis of the body member 15 for a purpose which will appear later.

The plug member 16 is of a generally cylindrical shape with a peripheral surface of an irregular contour. Referring to Fig. 2, the plug member 16 from its rear end 25 is formed in succession with a straight section 43, a forwardly and inwardly tapered section 44 and a head section 46 having a rim 47 at the rear end thereof. The tapered section 44 comprises a series of circumferential step portions 45.

The plug section 43 is inserted in a close fit within the section 27 of the bore 18 to a position defined by the engagement of its rear end 25 with a shoulder 48 formed at the junction of the bore sections 26 and 27. When thus positioned the head section 46 is located outwardly from the bore 18 and entirely forwardly of the front end 49 of the body member 15 and the inner or outlet ends 42 of the openings 41 are opposite the forward end of the stepped or tapered section 44 of the plug 16. It is seen, therefore, that the bore 18 is closed by the plug 16

at the front end of its section 26 and at a position forwardly of the transverse passage 29.

The casing 17 is of a hollow cylindrical shape having an open rear end 52 (Fig. 2) and a discharge orifice 53 at its front end. The orifice 53 is comprised of an outwardly and rearwardly tapered section 54 terminating in a straight section 56. The junction 57 of the straight section 56 for the main bore 58 of the casing 17 constitutes an annular shoulder or seat at the front end of the main bore 58 of the casing.

In the assembly of the casing 17 with the body member 15 and plug 16, the body member is received within the main casing bore 58 and 15 coaxing threaded portions 59 and 61 on the body member 15 and casing 17, respectively, are tightened until the body member front end 49 engages the shoulder 57. When the parts of 20 the nozzle are thus relatively positioned, the head 46 on the plug member 16 is arranged in a spaced relation entirely within the section 56 of the discharge orifice 53, and at a position rearwardly of the tapered orifice section 54.

Further, and as appears in Figs. 2, 3 and 4, the 25 side wall of the casing main bore 58 covers the grooves 31, 33, 34 and 38 formed in the outer peripheral surface of the body member 15 so that such grooves constitute a system of interconnected passages extended between the nozzle inlet 30 and the tangential openings 41, and terminating in the discharge orifice 53.

This passage system is best understood from a consideration of Figs. 6 and 8. For the purpose of convenience and clarity of description, 30 the grooves 31, 33, 34 and 38 will hereinafter be referred to as fluid passages. It is thus seen that the air and fuel mixture supplied to the inlet 30 is first divided at the transverse passage 29 for flow through the passages 29, 31 and 33. 35 Likewise, at the junction of the passages 33 with the passages 34 the mixture flow is again divided for travel through the passages 34 and 38 and openings 41. The mixture flow from the single inlet 30 is thus successively divided for flow 40 in four separate paths from the openings 41 and into the section 27 of the body member bore 18. 45

In order to eliminate any stratification of the air and fuel that might be present in the mixture supplied to the inlet 30, the rear end 25 50 of the plug 16 (Fig. 2) is located forwardly of the transverse passage 29, as was previously described, so that the portion of the bore section 26, between the passage 29 and the plug 16, defines an expansion or mixture receiving 55 chamber, indicated at 64, arranged as a forward extension of the inlet 30.

As the fuel flows through the inlet 30 its velocity 60 flow is increased by its travel through the tapered and restricted sections 22 and 23, respectively, prior to its admission into the chamber 64. Since the chamber 64 is of an enlarged diameter relative to the restricted section 24, the mixture is permitted to expand within the chamber 64 to accomplish a more thorough mixing 65 of the air and fuel therein. Further, the chamber 64 is of what might be termed an open type, namely, having an inlet and outlet arranged adjacent to each other, so that the mixture passing outwardly from the chamber 64 flows counter to and against the mixture entering 70 the chamber 64. As a result, the air and fuel in the mixture is further intermingled by its counterflow in the chamber 64 prior to its passage outwardly therefrom into the passage 75 29.

Substantially the same mixing action on the air and fuel takes place at the junctions of the circumferential passages 31 with the longitudinal passages 33, at which junctions the ends 32 of the passages 31 are extended beyond the rear ends of the longitudinal passages 33 to form open mixture receiving chambers designated at 66 (Figs. 2 and 3). The mixture from the passages 31 thus flows into the chambers 66 where it expands and then flows in a counter-relation against the fuel flowing toward the longitudinal passages 33.

In a like manner mixture-receiving chambers 67 and 68, provided at the junctions of the longitudinal passages 33 with the circumferential passages 34, and at the junctions of the circumferential passages 34 with the longitudinal passages 33, act in a manner similar to the chambers 64 and 66, to atomize and more uniformly disperse the fuel with the air, in the air and fuel mixture.

Further, as shown in Figs. 2, 6 and 7, the longitudinal passages 33 are of a reduced cross sectional area at portions 69 arranged rearwardly of their junctions with the circumferential passages 34, whereby to provide for an increased velocity flow of the mixture in such passages prior to the flow of the mixture into the chambers 68. It will be understood, of course, that these restrictions or chokes in the longitudinal passages 33 and circumferential passages 34 also permit a greater degree of expansion of the air and fuel mixture which enters the chambers 67 and 68.

As previously explained, the air and fuel mixture from the openings 41 is discharged with a swirling or spiral motion which results in the mixture being rotated about the stepped or tapered section 44 of the plug member 16 (Fig. 9). The mixture thus rotated moves forwardly about the tapered section 44 and against the rim 47 of the head section 46, and is thrown outwardly from about the rim 47 for discharge through the orifice 53 in a hollow cone shape. Because of the whirling or rotational movement of the mixture thrown outwardly from the head member 46, the heavier ends of the fuel tend to accumulate or collect in the form of a foam, indicated as 72, along the wall of the tapered orifice section 54. As the heavy fuel ends 72 reach the forward edge of the tapered section 54, they are picked up by the main body or flow of the air and fuel mixture through the discharge orifice 53 for thorough mixing therewith.

There is a tendency for some of the mixture from the openings 41 traveling upwardly or rearwardly on the tapered section 44. In the event this rearwardly moving mixture is permitted to accumulate about the rear portion of the tapered section 44, it will eventually break loose and move as a slug in droplet form into the discharge orifice 53. When this occurs the volume rate of mixture flow through the discharge orifice 53 is momentarily increased to in turn increase the size of the flame resulting from the burning of the cone shaped spray. This condition is eliminated by the stepped contour of the tapered section 44, since the fuel mixture tending to move rearwardly about such section, is progressively broken up by the steps 45 in the section 44 for travel in relatively small portions through the discharge orifice 53. As a result burning takes place at a substantially uniform rate and without any appreciable fluctuation in the size or intensity of the flame.

In the operation of an oil burner, it often happens that when the burner is shut off, fuel tends to accumulate at the discharge orifice 53 and travel rearwardly along the nozzle so as to be generally lost for burning purposes. In the present invention the front end of the casing 17 (Fig. 1) is formed with a rearwardly and outwardly tapered section 73 which is joined with a rearwardly and inwardly tapered section 74 so as to form a high spot or rib 76 about the casing 17. Thus any fuel that might drip from the discharge orifice 53 travels downwardly for collection on the rib 76 from where it drops away from the nozzle and into the supplementary air stream which generally flows about the nozzle.

In the use of the nozzle it is contemplated that the transverse passage 29 be arranged in a substantially horizontal plane. By this arrangement, if any stratification of the air and fuel in the mixture supplied to the inlet 30 is present, all parts of the stratified mixture will be acted upon uniformly in the mixture-receiving chamber 64. Further, in the event the spray is burning unevenly, that is, more lean on one side thereof than on the other, by merely rotating the nozzle about its longitudinal axis in the direction of the lean burning portion, the uneven burning of the spray will be completely eliminated.

Figs. 10, 11 and 12 show a modified form of the invention which is similar in many respects to the nozzle described in connection with Figs. 1 and 2, so that similar numerals of reference will be used to designate like parts.

The modified nozzle includes a body member 75, a plug member 76 and a casing 17. The body member 75 is formed with an axial bore 18 and a transverse passage 29 relatively formed and arranged in a manner similar to the bore 18 and passage 29 in the body member 15. The opposite ends of the passage 29 are open to the rear ends of a pair of longitudinal oppositely arranged grooves 77 formed in the peripheral surface of the body member 75. The plug member 80 is constructed with a straight section 78 received in the bore section 27 to a position defined by the engagement of its rear end 79 with the shoulder 48. An annular flange 81 on the front end of the straight section 78 is in seated engagement with the front end 82 of the body member 75 and is formed on its front side with a pair of oppositely arranged hollow involute or spiral portions 83 open at one end to the longitudinal grooves 77 and of a shape to provide for a whirling motion of the mixture discharged therefrom about a plug reduced section 85 which terminates in a head section 84. The cap member 17 is connected with the body member 75, in all respects similar to its connection with the body member 15, such that the head section 84 is disposed within the straight section 56 of the discharge orifice 53 and the grooves 77 are closed to form fluid passages.

In the operation of the modified form of the nozzle the air and fuel mixture supplied to the inlet 30 is thoroughly mixed and all parts of the fuel intermingled with the air on its passage through the tapered section 23, restricted section 24 and mixing chamber 64 in all respects similar to its passage through the like parts described in connection with Fig. 2. The mixture from the chamber 64 travels through the passage 29 and the longitudinal passages 77 for discharge through the hollow involutes 83 with a whirling motion for rotation about the reduced section 85

of the plug 76. The mixture is then thrown outwardly from the rear side 86 of the head member 84 for discharge through the orifice 53 in a spray of a substantially cone shape.

From a consideration of the above description, it is seen that the invention provides an improved nozzle and method for preparing or mixing an air and fuel mixture for efficient burning which is comprised of a relatively few number of parts of a simple construction capable of being easily and quickly assembled. Further, the nozzle is adapted for operation over long periods of time without servicing attention, since no critical adjustments are required to maintain its efficient operation. In actual practice air and fuel supplied to the nozzle, at pressures in the neighborhood of three to four pounds per square inch, is capable of being thoroughly mixed and atomized so as to provide a flame of uniform burning characteristics.

The nozzle provides for an even burning about the complete periphery of the cone shaped spray without any substantial variation in the intensity of the flame or in the position of the flame relative to the front end of the nozzle. The mixture-receiving and mixing chambers provided in the passage system in the nozzle effectively eliminate any stratification in the air and fuel that might be present in the mixture.

Although the invention has been described with respect to several embodiments thereof, it is to be understood that it is not to be so limited since changes can be made therein which are within the full intended scope of this invention, as defined by the appended claims.

I claim:

1. A nozzle for an oil burner comprising a body member formed with an axial bore having an internally threaded portion at its rear end for connection with a fuel supply pipe, and a horizontal transverse passage extended through said body member, with the outer peripheral surface of said body member being formed with a pair of oppositely arranged longitudinal grooves, and a pair of circumferentially extended grooves open at one of their ends to the outer ends of said transverse passage, and at their opposite ends open to the rear ends of said longitudinal grooves, with the front ends of said longitudinal grooves being connected with openings arranged tangential to said bore at a position adjacent to the front end of said body member, a plug member positioned within the forward end of said bore having its rear end spaced forwardly from said transverse passage, with the front end portion of said plug being of a reduced section opposite the inner ends of said tangential openings, a head portion on said plug member projected forwardly from the front end of said body member, and a cap member overlying said body member and plug having a fuel discharge opening opposite the front end of said plug member and covering said grooves so as to form fluid passages therewith.

2. A nozzle for an oil burner having an inlet for an air and fuel mixture and a discharge orifice, means fluid connecting said inlet with said orifice consisting of a single passage extended transversely of said inlet and arranged in a substantially horizontal plane, said inlet intersecting the passage intermediate the ends thereof so that the mixture from said inlet is discharged from opposite ends of said transverse passage, a pair of longitudinal passages, with each of said longitudinal passages having an end thereof connected respectively to an opposite end of said transverse passage, expansion chambers at the junctions of said transverse passage with said longitudinal passages, means for directing the air and fuel mixture from the other ends of said longitudinal passages in a spiral path for discharge from said orifice in a spray form for flame burning, and means supporting said nozzle for rotational movement about the longitudinal axis therefor, whereby the burning of the discharged spray in an even flame is controlled by rotation of the nozzle in the direction of the lean burning portion of the flame.
3. A nozzle for an oil burner having an axial air and fuel mixture inlet at its rear end and a discharge orifice at its front end, a passage system fluid connecting said inlet and orifice comprising a transverse passage arranged in a substantially horizontal plane and extended across the front end of said inlet so as to be in fluid registration intermediate its ends with said inlet whereby the mixture from said inlet is discharged from opposite ends of said transverse passage, a pair of longitudinally extended passages, with each of said longitudinal passages being connected at the rear end thereof to an opposite end of said transverse passage, a mixing chamber located opposite the front end of said inlet so that a portion of the mixture from said inlet flows in reversed directions in said mixing chamber prior to the flow of said mixture toward the opposite ends of said transverse passage, and means adjacent the outlet of said passage system for imparting a swirling motion to the mixture discharged from said orifice.
